UNITED STATES PATENT OFFICE

2,474,579

HOE STAND

John F. Hendrix, Munday, Tex.

Application May 3, 1946, Serial No. 667,033

3 Claims. (Cl. 51—216)

1

This invention relates to stands for retaining garden implements for sharpening, and more particularly to such devices especially adapted for holding a garden hoe.

Gardening and weeding hoes are usually sharpened by passing a mill file angularly across the cutting edge of the blade, thus requiring means for holding the blade in a rigid position while in the process of sharpening, and thereby permitting greater efficiency during the process and providing greater safety to the person engaged in the process of sharpening.

The principal object of the invention is to provide means for holding a hoe blade rigidly in position for sharpening, utilizing the end of the hoe handle as one leg in forming a tripod in conjunction with the invention herein described.

Another object of the invention is to provide a blade-conforming shoulder in a stand as means for securing the blade in proper position for sharpening.

Still another object of the invention is to provide a lateral member in a sharpening stand as means for clamping the ferrule on the end of the hoe handle when pressure is applied downwardly upon the hoe handle.

With the foregoing objects as paramount, the invention has further reference to certain features of accomplishment which will become apparent as the description proceeds, taken in connection with the accompanying drawings, wherein:

Figure 1 is an end elevational view of a hoe sharpening stand constructed according to the invention showing a hoe in phantom relationship therewith.

Figure 2 is a side perspective view of the hoe stand to illustrate in greater detail a blade-conforming shoulder in a lateral member adapted to receive the back of a hoe blade.

Figure 3 is a side elevational view of the invention showing a hoe in position for sharpening, and

Figure 4 is a perspective view of a modified form of the invention utilizing angle iron in its construction.

Continuing with a more detailed description of the drawings, a pair of upright members 10 serve as the two legs of the invention, having a cylindrical lateral spacing member 11 for maintaining rigid spaced relationship between the ground engaging ends of the legs 10. A block 12 is permanently secured to the legs 10 adjacent their upper ends, acting as a clamping member as will be more fully described hereinafter.

2

A laterally disposed blade holder 13 is fastened to the front edges of the legs 10 as illustrated in Figures 1, 2, and 3. In this instance the blade holder 13 is a portion of shiplap lumber, the lip 5 along the upper edge forming a shoulder to support the back of a hoe blade in a rigid horizontal position while sharpening the cutting edge of the blade 14. The holder 13 is inset flush with the edges of the legs 10 for greater stability and 10 more pleasing appearance. A notch 15 in the holder 13 is provided to permit a hoe handle 16 to pass therethrough in placing the blade 14 in proper position for sharpening, the end of said handle 16 being a ground engaging third member 15 of a tripod stand thus formed in conjunction with the legs 10.

In use as a sharpening stand the handle 16 and blade 14 are placed as described previously, and downward pressure is exerted upon the handle 20 16 near point *a* by the person engaged in sharpening the blade 14. This is usually accomplished by placing a knee upon the handle 16 and permitting a part of the body weight to rest thereon. This downward pressure upon the handle 16 25 causes said handle 16 to assume the slightly arcuated contour illustrated by the dash lines in Figure 3. This procedure reacts in like manner upon the legs 10 and its attached members, causing the stand to assume the approximate position also shown in dash lines in Figure 3.

It will be noted that as the stand moves to assume the position previously described the block 12 will bear more and more firmly upon a ferrule 17 at point *b*, thus acting as the fulcrum 35 of a lever in bringing the back of the blade 14 into rigid engagement with the shoulder provided therefor on the holder 13. Thus, in effect, the block 12 bearing upon the ferrule 17 and the holder 13 supporting the blade 14 form a means 40 for rigidly securing the blade 14 while in the process of sharpening. It should be further noted that the notch 15 in the holder 13 is of sufficient capacity to receive hoes having a variety of eight diameters in order that the previously described 45 clamping effect may be freely accomplished.

A modified form of the invention is illustrated in Figure 4, in which legs 18 are constructed of angle iron. A spacing bar 19 is welded to the inner surfaces of the legs 18 serving in the capacity 50 previously ascribed to the spacing member 11. The upper ends of the legs 18 are welded together to form a rigid frame. A pair of short sections of angle iron 20 are welded transversely of the frame as illustrated, having a portion of 55 each section removed to form a shoulder for re-

taining the back of the hoe blade 14 while being sharpened. The juncture of the inner surfaces of the legs 18 acts upon the ferrule 17 of the handle 16 in practically the same manner described relating to the block 12 of the preferable embodiment of the invention.

Manifestly, the construction as shown and described is capable of some modification and such modification as may be construed to fall within the scope and meaning of the appended claims is also considered to be within the spirit and intent of the invention.

What is claimed is:

1. A hoe sharpening stand including an A-frame, a hoe blade retaining member fixedly disposed transversely on one side of said frame in spaced relation to the apex thereof and provided with a gullet to receive the handle of said hoe blade, the end of said handle being adapted to engage the ground in spaced relation to said stand in support thereof, a second transverse member on the opposite side of said stand and above said first member adapted to exert a downward thrust on said hoe handle in tilted position of said frame to clamp said hoe in said frame. 15

2. A hoe sharpening stand including an A-frame, a spaced parallel hoe blade retaining member stationarily disposed transversely on said frame adjacent the apex thereof and adapted to receive the back of said hoe blade, the handle 20

10

of the latter being adapted to extend from said frame and engage the ground at a point spaced therefrom to support said frame in an operatively inclined position, a rigid member carried by said frame above and in parallelism with said first member and adapted to exert a downward thrust on said hoe handle to clamp the same in said frame.

3. A hoe sharpening stand comprising an A-frame, a transversely disposed blade retaining member affixed to one side of said frame, and recessed to receive a hoe blade, the handle of the latter extending rearwardly of said frame and engaging the ground to support the frame in an operative position, and a second transverse member affixed to the opposite side of said frame adjacent the apex thereof in spaced parallelism with said first member and under which said hoe handle is adapted to extend.
